UNITED STATES PATENT OFFICE

2,599,294

CIRCUIT RESTORER

Carl Thumim, Yeadon, Pa., assignor to General
Electric Company, a corporation of New York

Application April 6, 1948, Serial No. 19,249

4 Claims. (Cl. 200—89)

1

This invention relates to circuit breakers and more particularly to automatically operable circuit interrupters of the recloser type which are now frequently designated by the term "oil circuit restorers."

More specifically my invention is an improvement on the device disclosed in Patent 2,069,082—Walle issued January 26, 1937 and assigned to the assignee to whom this application is assigned. The interrupter disclosed and claimed in the above patent to Walle is capable to time-delayed reclosing operations only, while my invention provides complete coordination among associated reclosers or fuses provided in a sectionalized distribution system and affords both time-delayed and substantially instantaneous opening operations as well as time-delayed reclosing operations.

Accordingly it is an object of my invention to provide an automatically operable reclosing circuit interrupter having improved operating characteristics wherein provision is made for time-delayed opening and time-delayed reclosing operations should the fault condition be persistent in nature.

Another object of my invention is the provision of an operating mechanism for automatically operable reclosing circuit interrupters wherein a predetermined number of time-delayed opening and reclosing operations are utilized to cause the mechanism automatically to lock its contacts in the open circuit position should the fault condition be persistent in nature.

Still another object of my invention is to provide an operating mechanism for automatically operable reclosing circuit interrupters wherein a member is caused to rotate in response to time-delayed opening and reclosing operations and thereafter to cause the mechanism automatically to lock its contacts in the open circuit position where a persistent fault occurs on the line.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawings in which Fig. 1 is an elevational view partially in section of a recloser embodying my invention; Fig. 2 is an enlarged view of the timing mechanism embodying my invention wherein the respective parts occupy the positions which they assume when the interrupter contacts are closed when normal current is flowing through the interrupter; Fig. 3 is a view similar to Fig. 2 wherein the positions of the parts are shown during the first reclosing operation following an instantaneous opening operation; Fig. 4 is a view similar to Figs. 2 and 3 wherein the parts are shown in the positions which they occupy during the first time-delayed opening operation; Fig. 5 is a view similar to Figs. 2 through 4 showing

2

the mechanism in the locked-open position; and Fig. 6 is a view partially in section of the upper end of the movable contact rod and parts associated therewith.

With reference to Fig. 1 the interrupter is provided with a pair of terminals 1 and 2. Terminal 1 is mounted on and supported by the metallic domed cover 3 which in turn is secured to the porcelain housing 4 in any suitable manner such as by the bolts 5 through adapter rings 6 and 7. Ring 7 is secured to the housing 4 by any suitable means such as by the cement 8. A sealing washer 9 is disposed between the adjacent surfaces of the adapter ring 7 and the upper end of the porcelain housing 4. A sealing washer 10 is disposed between the adjacent surfaces of the adapter rings 6 and 7. The interrupter is provided with a metallic supporting band 11 disposed about the outer surface of the porcelain housing 4. Suitable means, now shown, are secured to the band 11 for mounting the interrupter. I have shown the relatively soft gasket 12 disposed between the clamping band 11 and the porcelain housing 4 for securing a snug seating joint therebetween.

The line terminal 2 is provided with an internal conducting flanged portion 13. The nut 14 is provided to hold the flange 13 against the washers 15 and 16 so as to afford a fluid-tight seal between the flange 13 of the terminal 2 and the opening in the bottom of the housing 4 which is not shown and through which the terminal stud 2 extends.

The whole structure within the housing 4 is supported by a plurality of bolts such as 17 which are secured to the cover 3 in any suitable manner. The bolts 17 support the plates 18 and 19 which are held in spaced relation by the lower sleeves 20 which surround the bolts 17. The plate 19 is spaced a suitable distance from the cover 3 by suitable upper sleeves 21 which surround the bolts 17. The portion so far described is not my invention but is rather like the housing structure disclosed in the U. S. Patent 2,414,786 to Lincks et al. which is assigned to the same assignee as this application.

The timing mechanism is mounted upon a frame comprising spaced plates one of which is indicated by 22 which in turn is provided with appropriate inturned feet or flanges such as 23 which in turn are secured to the plate 19 by welding or by any other suitable means. The operating or sensing coil 24 is supported between the plates 18 and 19, while an armature guide bushing 25 clamped therebetween also provides centering means for the coil spool. The arcing chamber generally designated at 26 comprises a lower plate 27 of insulating material and a cylindrical casing wall 28 also of insulating material. Plate 27 is supported insulatingly from the metallic plate 18 by means of a plurality of bolts 29 and 30 screwed into insulating columns one of which is indicated by 31. An oil expul-

sion port 35 permits the escape of interrupting pressure fluid from within the arcing chamber 26 into the surrounding chamber formed within the housing 4, in which oil is contained up to the approximate level indicated in Fig. 1.

Also as in the aforesaid Lincks et al. patent, a somewhat resilient connection between the fixed arcing contact 36 and the flanged portion 13 of the terminal stud 2 is afforded by the U-shaped member 34 which is pressed into abutting engagement with the terminal flange 13 by the small compressional spring 37 which insures good contact between the arcing contact 36 and the terminal 2. The adjusting nut 38 which is held in position by the lock nut 39 serves to hold the member 34 in place. A suitable washer such as the cup-shaped member 40 may be provided to absorb the shock when the contacts close.

Cooperating with the fixed interrupting contact 36 there is shown a movable contact 41 which is secured to the contact rod 42. The contact rod 42 is disposed within an armature 43 constructed of magnetic material such as iron. Armature 43 is guided by the sleeve 56a and the aforementioned bushing 25. Secured to the upper end of the armature 43 so as to constitute a light-weight extension thereof is a sleeve 44 constructed of non-magnetic material such as brass. Disposed about the contact rod 42 and inside the sleeve 44 is a compressional spring 45 which engages at its lower end the upper end of the armature 43. The upper end of the spring 45 engages the terminal block 46 which is threadedly secured to the contact rod 42 at its upper end as can best be seen in Fig. 6. Accordingly, the spring 45 provides a resilient coupling and lost-motion means between the contact and its actuating armature.

The complete circuit through the interrupter is not shown in the drawings and hence will be described in detail. As will be seen from Fig. 6, the terminal block 46 is provided with a terminal screw 47 to which is connected a flexible conductor 48. Flexible conductor 48 is connected to one end of the coil 24 while the other end of the coil 24 is connected to the terminal 1. The circuit through the interrupter comprises the terminal 2, the member 34, the fixed contact 36, the movable contact 41, the contact rod 42, terminal block 46, flexible lead 48, operating coil 24, and through a conductor, not shown, to the terminal 1.

Thus it will be seen that the operating coil 24 is in series with the line circuit and hence carries the load current. Should the current through the interrupter be in excess of a predetermined amount, the armature 43 will be elevated together with the sleeve 44. The terminal block 46 remains stationary with the contact 41 for the latter remains in engagement with the fixed contact 36 for a predetermined time after the initiation of the upward movement of armature 43 as will be more fully understood as the description proceeds.

Comparing Fig. 1 with Fig. 6 it will be observed that the terminal block 46 constitutes a transverse crosshead atop the contact rod 42, the ends of which receive a pair of links 56 and which overhang beyond the armature tube 44. Hence for permitting telescoping relative movement between contact rod 42 and the armature 43, a pair of vertical slots 44a are provided in the upper end of the armature tube 44 within which slots the block or crosshead 46 may slide whenever telescoping movement occurs.

For the purpose of latching the contact 41 in the downward or closed position, the latching member 50 which is pivotally mounted at the fixed pivot 51 to the supporting plate 22 engages the restraining pin 52 mounted across the forked arms 53. Arms 53 are pivotally mounted to the plate 22 by a fixed pin 54 and are pivotally connected at their free ends by the pins 55 to the pair of vertical links 56. Links 56 are pivotally connected by the pins 57 to the terminal block 46, as best shown in Fig. 6. Thus with latch 50 occupying the position shown in Figs. 1, 2 and 4, the contact rod 42 is effectively latched in the down or closed position. The curved surface of the latch 50 which, as shown in Figs. 1, 2 and 4 is in engagement with the pin 52, is eccentric with respect to the pivot pin 51 to provide for contact wear. As wear takes place, the contact rod's closed position is slightly lower and the latch 50 wedgingly assumes a lower or deeper engagement with respect to pin 52.

For unlatching the closed contact 41 only in the event that a predetermined overcurrent flows through the series coil 24, i. e. only when the armature 43 has lifted substantially a full stroke, I couple the contact latch 50 to the armature sleeve extension 44 by means of the slotted link 61. The upper end of this link is connected by pivot pin 62 through the lug or bracket 60 which is affixed to the upper end of armature sleeve 44, while the slot 63 in link 61 rides about a pin overhung from the latch 50. Accordingly, the armature must move upwardly somewhat more than the length of the slot 63 before the contact 41 unlatches, at which point the now compressed spring 45 will cause the crosshead 46 and its depending contact structure to move upward to circuit-open position.

For the purpose of manually lifting the armature for operating the above contact opening mechanism, I provide a connecting link 65 which is pivoted at its lower end by pin 62 to the lug 60 and which is pivotally connected by its upper pin 66 to the internal arm 67 of an offset bell crank. The external arm 69 of the offset bell crank, which projects from a pocket provided in the cover 3, is rigidly coupled to the internal arm 67 by means of their common keyed shaft 68 which is suitably journaled in the cover 3. The outer end of the external arm 69 is provided with an opening 70 through which a hooked stick may be inserted and moved downwardly for the purpose of elevating the left hand end of the arm 67 thereby to open the contacts as already indicated.

In order to lock the contacts in the open position upon completion of a manual opening movement, I provide an external latch 71 which is pivoted to a projecting hood portion of the cover 3 by a fulcrum pin 72 and which is frictionally held in a particular position by the action of compression spring 73 as disclosed more fully in the above-mentioned Lincks et al. patent. The latch 71 is constructed with a latching surface 74 toward its upper end. Mounted on the manual crank arm 69 is a projecting stud 75 which catches under the latching surface 74 of the latch 71 when the external arm 69 is moved downwardly to open contact position. In order to release the latch, it is only necessary to push upwardly on the surface 76 of the latching member 71 to cause the surface 74 to disengage the stud 75 and thereby to permit counterclockwise movement of the bell crank which in turn permits the link 65, the sleeve 44, and the armature 43 to move downwardly together with the

contact rod 42 and the contact 41 to the contact closed position.

It will be understood that my invention could be adapted to perform, within limits, a relatively wide range of opening and closing operations wherein certain of these operations would be time-delayed and wherein certain others would be made to occur almost instantly. For persistent faults, the particular embodiment of my invention shown in Figs. 1 to 5 is adapted to perform a first instantaneous opening operation followed by a predetermined number of time-delayed opening operations while, at the same time, retaining the capability of performing a time-delayed closing operation following each opening operation as in the aforementioned Walle patent irrespective of whether the opening be instantaneous or time-delayed. More specifically, the about-to-be-described timing mechanism of my invention provides for, in the event of a sustained fault circuit above a predetermined current magnitude, the following operating sequence or cycle: (a) a substantially instantaneous opening; (b) a time-delayed reclosure; (c) a time-delayed opening; (d) a second time-delayed reclosure; (e) a second time-delayed opening; (f) and final lock-out in the open position.

The above identified sequence of operations is governed by the timing mechanism generally indicated by the numeral 80. In this device 80 of my invention, I employ a time-delaying element, preferably of the mechanical escapement type, which is driven for an intermittent period during each reclosing movement as in the aforementioned Walle patent; and furthermore, I drive this same time-delaying element for an intermittent period, and selectively, in accordance with certain predetermined opening operations. In addition, I cause a lock-out producing member to be advanced through a predetermined increment whenever a delayed reclosing or delayed opening operation is effected by the retarding action of the said time-delaying element so that ultimately, at the termination of the predetermined reclosing cycle, the total displacement of said lock-out member has conditioned the device for preventing a further reclosure of the interrupter contacts.

For the purpose of governing the opening characteristics of the device 80, there is provided a pivoted carrier member 81 which is supported near its mid-point for rotation about the shaft 82 which is journally mounted in the frame comprising at least one side plate 22. Carried by the left hand end of the member 81 is what conveniently may be identified as the "opening" gear 83 which at all times is in mesh with the teeth of the gear 84 which is secured to and rotatable with the shaft 82. A tension spring 85 biases the carrier member 81 for rotation in the clockwise direction about the shaft 82. The carrier 81 is prevented from rotating clockwise when the mechanism is in the position shown in Figs. 1 and 2 by the crank pin 90 which overhangs the rear surface of the gear wheel 87. Gear wheel 87, which is the lock-out producing member of my device, is mounted for rotation about the shaft 88 and is biased for rotation in the counterclockwise direction about the shaft 88 by its spiral resetting spring 89 one end of which is fixed to the near side of the supporting frame. A crank pin 86 also overhangs from the front surface of gear wheel 87 for the lock-out purpose which will become apparent hereinafter.

The carrier member 81 cannot rotate counterclockwise from its normal position as shown in Figs. 1 and 2 because of the fixed pin 71 which acts as a stop.

5 The rack 91, which constitutes a clutch member whereby intermittent coupling between the contact structure and the timer mechanism 80 is accomplished, is secured to the armature sleeve 44 and hence is movable therewith. The pin 58, which is secured to the plate 22, acts as a guide for sleeve 44 and is positioned as shown for countering the lateral thrust component to be applied to the rack. With reference to Figs. 1 and 2, it will be seen that the rack 91 is free 10 to move without engaging the teeth of the opening gear 83. Thus, a first opening operation is made substantially instantaneously since the opening gear 83 is maintained by its carrier 81 out of engagement with the rack 91 due to the interference of the crank pin 90; hence no movement whatever of the timer device 80 is produced coincident with this initial opening stroke of the armature 43.

For the purpose of accomplishing time-delayed closing operations, I provide what may be conveniently termed the "closing" gear 92 which is journalled at 93 into its carrier member in the form of an arm 94 which in turn is pivoted about the fixed shaft 95. Arm 94 is biased against the 25 fixed stop 96 by the tension spring 97 but is free to move a limited amount in the clockwise direction about the shaft 95 until the arm 94 encounters its other stop 98. A gear 99 is rotatable about the shaft 95 in response to rotation of the 30 closing gear 92 for gears 92 and 99 are in mesh at all times. The gear 100 is secured to the gear 99 and hence rotates therewith about the shaft 95. Mounted on the shaft 101 and meshing with gear 100 is a pinion 102 which is secured to the 35 timer ratchet wheel 103. An oscillatory verge member 104 constitutes a common watch escapement with the ratchet wheel 103 to produce a retarded or time-delayed rotation thereof in a manner well known in the art. Thus, the closing gear 92 is always connected to the timer ratchet 103 through the above gear train. For intermeshing the opening gear 83 to the same timer ratchet 103, I have mounted for rotation about the shaft 105 a large gear 106 which meshes with 40 the timer pinion 102. Secured to the gear 106 and rotatable therewith is a pinion 107 which engages the teeth of the gear 108 which in turn is secured to and rotatable with the shaft 82 which, as pointed out above, is journally mounted 45 on the supporting plate 22. Because the pinion 107, as well as the gears 84 and 108 are all secured to their common shaft 82, all these members 50 rotate as a unit.

From the above explanation it will now be 55 appreciated that whenever the closing gear 92, or the opening gear 83, is caused to rotate, as by meshing engagement with the rack 91, then such rotational movement will be subject to the retardation of the escapement device or verge 104 due 60 to the complete and positive intermeshing of the above-described trains of gears. Furthermore 65 and for the same reason, it will be understood that any rotation of either the closing or the opening gear will produce a corresponding rotational increment of the lock-out gear 87, each 70 increment being in the same clockwise rotational direction.

When a current through the interrupter exceeds a predetermined value, the coil 24 will be 75 energized sufficiently to elevate the armature 43,

the sleeve 44, the supporting member 60, the links 61 and 65 (accompanied by clockwise rotational movement of the bell crank comprising arms 67 and 69) as well as the gear rack 91. The gear rack 91 moves freely past the opening gear 83 since from Figs. 1 and 2 it will be evident that this gear is out of the path of motion of the rack 91. However, the closing gear 92 does lie in the path of the rack, although, when the rack 91 strikes the closing gear 92, its carrier arm 94 is rotated in the clockwise direction about the fixed shaft 95 through a relatively small angle limited by the stop 98 so that the gear 92 is in effect merely brushed aside by the rack 91 until the rack 91 and parts associated therewith will have reached the upper limit of travel, i. e. when the armature 43 strikes its guide bushing 56. Coincident with downward movement from this extreme upper position, the rack 91 will intermesh with the closing gear 92 due to the resetting action of tension spring 97 and the thrust relationship which is now established between the carrier arm 94 and the rack 91 so that the latter now is connected in driving engagement with the timer mechanism 80.

Because of the resilient drive afforded by the spring 45 between the armature 43 and the contact structure through the crosshead 46, it will be perceived that contact 41 will be lifted from contact 36 as soon as it is unlatched which unlatching occurs toward the end of the armature upward travel as will now be explained in detail. As the armature 43, the sleeve 44, the supporting member 60 and the link 61 move upwardly, the pin 64 on the latch 50 rides in the slot 63 so that, when it is picked up by the lower end of the slot 63, the latch 50 is rotated in the counterclockwise direction about its pivot 51. This action moves the latch 50 out of engagement with the pin 52 and permits the arm 53 to rotate counterclockwise about its pivot 54 thereby permitting the links 56, the crosshead 46, the contact rod 42 and the contact 41 to move together rapidly upward thereby to part the contacts 36 and 41 for drawing and extinguishing an arc therebetween. The oil blast generated within the arcing chamber 26 is expelled through the port 35 in the pressure confining casing 28.

After the rack 91 has enmeshed the closing gear 92 as explained above, the armature 43 and contact parts associated therewith move downwardly in unison under the reclosing force of gravity. Because the rack 91 now is in driving engagement with the closing gear 92, this gear will be rotated in the counterclockwise direction which causes the gear 99 and the gear 100 to rotate clockwise. This action through the timer pinion 102 causes the gear 106 and pinion 107 to rotate clockwise which in turn causes the united gears 108, 84 and pinion 79 to rotate counterclockwise. This train of action causes the gear wheel 87 to rotate clockwise against the bias of its resetting spring 89 resulting in a predetermined increment of advance of the pin 90 in the clockwise direction. Accordingly the pin 90 will ride out from under the lower right hand end of the carrier member 81 so that the spring 85 is effective to rotate the carrier 81 from the position shown in Fig. 2 to the limiting position shown in Fig. 3 thereby placing the opening gear 83 in the path of the now slowly descending rack 91. As the rack 91 disengages the closing gear 92, the rack and parts associated therewith are free to drop without further effective impediment, because the opening gear 83

is merely brushed aside by the rack 91 during this reclosing operation in a similar manner as described for the closing gear 92 in the opening operation and no significant time-delay is attributable to this incidental non-meshing action.

While the first portion of the above-described reclosing downward movement is taking place, i. e. while closing gear 92 and rack 91 are in mesh, the ratchet wheel 103 introduces a time-delays action since the ratchet wheel is secured to and rotatable with the timer pinion 102 and is retarded by the oscillatory action of the verge member 104.

After the mechanism has opened substantially instantaneously and reclosed with time-delay as described, the carrier 81 will occupy the above-mentioned interfering position so that, if the fault persists, a second opening operation will occur which, unlike the first, will be attended by the rack 91 meshing with the opening gear 83 during the armature's upward travel as shown in Fig. 4 so that the lock-out gear wheel 87 is rotated a further increment in the clockwise direction by the action of pinion and gear 79 and 84 which are interposed between the opening gear 83 and the gear wheel 87 as explained above. This opening movement is accompanied by time-delay due to the action of the oscillatory verge member 104 as in the time-delay reclosing movement. When the rack 91 moves out of mesh from the opening gear 83, the rack and mechanism associated therewith become free to move upwardly without further significant impediment, since the rack will now proceed to brush the closing gear 92 to the right without effect as previously explained.

At this point, it will be understood that, during the period the timer mechanism 80 has been coupled by the opening gear 83 through the rack 91 to the armature structure, the latter has not lifted sufficiently high for unlatching the closed contacts. Thus they have been maintained closed following the first reclosure for a predetermined time-delay, so that here an opportunity is provided for the fault circuit to burn itself clear. It will also be appreciated that the gear ratios of the train between the timer ratchet 103 and the opening or closing gears respectively may be chosen so that appropriate time-delays are produced for either the delayed opening or closing operations. For example, in the embodiment shown, I provide for much greater resistance during opening than closing, in view of the higher opening forces encountered, by gearing for a greater number of oscillations of the control verge member 104 in the case of the delayed opening compared to the delayed closing operation.

When the rack has reached the uppermost position, the contacts will have separated and the closing gear 92 will intercept and engage the rack 91 as it descends as previously explained so that a second reclosing operation will be accomplished with time-delay which will result in a further increment of rotation of the gear 87 which further advances the crank pins 86 and 90 projecting therefrom.

If a fault persists it will be understood that a predetermined number of above-described time-delayed opening and reclosing operations will continue in rapid intermittent sequence, each one of which will produce a further increment of advance to the lock-out gear 87. This gear's intermittent clockwise rotation will proceed with negligible back-tracking from return spring 89

for the reason that practically no time elapses between the reclosure of the contacts and the reenergization by the fault current of the coil 24; accordingly, the total angular displacement of the lock-out gear 87 is substantially the sum of all the intermittent closing and opening angular increments produced during the whole predetermined reclosing cycle, assuming of course, that a permanent fault is involved. It further will be appreciated that the gear reduction between the lock-out gear 87 and the opening or closing gears may be chosen for producing predetermined angular increments of advance for the delayed closing or opening operations respectively. In my chosen embodiment depicted in the drawings, I have shown an arrangement in which the closing increment for the gear 87 is small compared to the larger opening increment.

From the above explanation it will be discerned that I may terminate the reclosing cycle after a predetermined number of reclosures by applying means for arresting the angular advance of the gear 87, for in so doing the whole gear train of the timer mechanism 80, including the closing and opening gears, is prevented from further rotation. Moreover, it will be understood that stoppage of the gear 87 during a reclosing cycle will result in locking the recloser either in the contact open position on the one hand or in contact closed position on the other, depending on whether such stoppage occurs while the gear 87 is advancing through a closing increment as in Figs. 3 or 5, or through an opening increment as in Fig. 4. In other words, stopping the gear 87 will stall the contacts either in the open position, i. e. when the rack 91 is in mesh (or about to enmesh) with the closing gear 92; or, on the other hand, it will stall the contacts in the closed position, i. e. when the rack 91 is in mesh (or about to enmesh) the opening gear 83. Accordingly, I may provide suitable stop means in the path of the lock-out gear's crank pin 86 for terminating the reclosing cycle after a predetermined number of reclosing operations. I can predetermine the position of the stop so that it is effective for establishing a final lock-out position for the contacts on the one hand as in the aforesaid Walle patent; or, on the other hand, I may choose to position the stop in another location so that the contacts finally become locked closed, as in the aforesaid Lincks et al. patent.

I provide such a stop in the form of the pin 110 which is shown in the slot 111 of a fragment 112 of the mechanism supporting frame. Obviously I may affix this stop in any location within the slot for predetermined interference with the closing gear's crank pin 86 for terminating the reclosing cycle with either a lock-open or lock-closed final position for the contacts. Furthermore, it will be apparent that a conversion from the lock-closed to the lock-open setting (or vice versa) is effected merely by unfastening the stop pin 110 from one position and installing it in an alternative blocking position.

Because it is more common to arrange oil circuit restorers for terminating their reclosing cycle with the contacts left open, I have arranged the final stop means in the chosen embodiment as depicted in the drawings so as to insure contact lock-out, that is, with the rack 91 hanging on the stalled closing gear 92 as in Fig. 5, irrespective of whether or not the lock-out gear 87 is arrested during a closing incre-

ment, or perhaps inadvertently, during an opening increment. To this end, I arrange the stop pin 110 so that it will block the crank pin 86 from further rotation after the gear has rotated one complete revolution, in other words, just when the gears of the crank pin 90 has advanced to its original position as seen in Fig. 2 so that it again clears the carrier member 81 with its opening gear 83 clear of the rack 91 as depicted in Fig. 5. Accordingly with this arrangement, if it should happen that the pin 110 stops motion of the gear train by blocking the crank pin 86 at any time other than when the gear 91 and the closing gear 92 are enmeshed, the energized coil 24 would instantly raise the armature and contact structure to the lock-out position shown in Fig. 5 for the reason that the opening gear 83 has been rendered non-interfering by the pin 90. In this arrangement I provide for a full 360 degree rotation of the lock-out gear 87, as illustrated during the cycle of Figs. 2 through 5, by supporting the stop pin 110 slidably, rather than fixedly, within the slot 111. Consequently, in the normal or reset contact closed position of Figs. 1 and 2, it will be noted that the lock-out gear's resetting spring 89 has caused crank pin 86 to move the stop pin 110 to the right hand end of slot 111; while, at the completion of the reclosing cycle as depicted in Fig. 5, the pin 110 has been moved over by crank pin 86 to the other end of the slot in which it assumes its locked-open stop position. By comparing Figs. 2 and 5, it will be evident that this lost-motion stop device constituted by the pin 110 in the slot 111 provides for the full 360 degree rotation of the crank pin 90 whereby the reclosing cycle both commences and terminates with the opening gear 83 held in non-meshing position. For the above described arrangement, it will be understood that I have selected gear ratios which will give appropriate closing and opening increments so that the predetermined number of reclosures will have been effected when the lock-out gear 87 has rotated through one complete revolution.

In its broader aspects, it will be perceived that the above-described timer mechanism 80 of my invention may be regarded as comprising a pair of delay producing pawls; one of which is a closing pawl constituted by the gear 92 and its carrier arm 94, and the other an opening pawl constituted by the gear 83 and its carrier member 81, with means provided for rendering the opening pawl inoperative at appropriate times during the reclosing cycle.

The indicator tabs marked "closed" and "open" in Fig. 1 are disposed opposite the right hand end of the external crank arm 69 and hence serve as indicators to the observer to show whether the contacts are in the opened or the closed positions.

If the breaker is locked open after a persistent fault, or remains closed after one or more reclosures because the fault meanwhile has cleared, the spring 89 thereafter will rotate the gear wheel 87, together with the gears constituting the whole train, back to the reset position shown in Figs. 1 and 2 with the pin 90 once more underneath the lower right hand surface of the carrier member 81 and with the lock-out pin 86 engaging its limiting stop 110. This resetting movement will be slow because the timer ratchet 103, of course, is always in mesh with the gear train.

After the manual release by the latch 71 from a manual opening operation, it will be clear that the contacts will close with time-delay because

of the rack 91 meshing with the closing gear 92. Accordingly, lock-out gear 87 rotates resulting in the movement of pin 90 away from the holding position with respect to carrier member 81 so that the opening gear 83 assumes its pick-up position in the path of the rack. Therefore, any immediate tendency to re-open is prevented so that, if high transients as from starting loads exist temporarily, the device will not operate to open and close its contacts unnecessarily.

While I have shown and described a particular embodiment of my invention, it will be obvious to those skilled in the art that various changes and modifications may be made without departing from my invention in its broader aspects and I, therefore, intend in the appended claims to cover all such changes and modifications as fall within the true spirit and scope of my invention.

What I claim as new and desire to secure by Letters Patent of the United States, is:

1. In an electric circuit reclosing device, relatively movable contacts biased into engagement, electromagnetic means for initiating an opening operation of said device in response to predetermined fault conditions, means responsive to operation of said electromagnetic means for opening said contacts, a rotatable timing member, a rack movable in accordance with the operation of said electromagnetic means and in accordance with closing movement of said contacts, a closing gear operatively connected with said timing member and rotatable in response to closing movement of said rack to determine the time required automatically to reclose said contacts after an interrupting operation, an opening gear operatively connected with said timing member, and means movable in response to closing movement of said contacts to cause said opening gear to engage with said rack during an opening movement of said rack for rotating said member to control the time required to open said contacts during preselected opening operations of said contacts.

2. In an electric circuit reclosing device, relatively movable contacts biased into engagement, electromagnetic means for sensing predetermined fault conditions of the controlled circuit and for initiating an opening operation of said device in response to such fault conditions, means responsive to operation of said electromagnetic means for separating said contacts, a rotatable time delay member, a rack movable in response to operation of said electromagnetic means, an opening gear operatively connected with said member and rotatable by said rack in response to an opening operation of said rack which closely succeeds a prior opening operation thereof for rotating said rotatable member to delay opening of said contacts during preselected opening operations of said contacts, a closing gear operatively connected with said member and rotatable in response to closing movement of said rack for rotating said rotatable member to delay closing of said contacts, a stop member, and a pin on said rotatable member for engaging said stop member after a predetermined angular rotation of said rotatable member to prevent further rotation of said rotatable member thereby to cause said contacts to be locked in the open circuit position upon engagement of said rack with said closing gear.

3. In an electric circuit reclosing device, relatively movable contacts biased into engagement, electromagnetic means for sensing predetermined

fault conditions of the controlled circuit and for initiating an opening operation of said device in response to such fault conditions, means responsive to operation of said electromagnetic means for separating said contacts, a rotatable member, a rack movable in response to operation of said electromagnetic means and in accordance with closing movement of said contacts, a timing mechanism, a closing gear rotatable in response to closing movement of said rack for rotating said member and for operating said timing mechanism to determine the time required automatically to reclose said contacts after an interrupting operation, an opening gear operatively connected with said timing mechanism, and means movable in response to closing movement of said contacts to cause said opening gear to engage with said rack during an opening operation of said rack for rotating said member and for operating said timing mechanism to control the time required to open said contacts during preselected opening operations of said contacts, and means for limiting the rotation of said member to a predetermined amount to lock said closing gear against closing rotation thereby to hold said contacts in the open circuit position.

4. In an electric circuit reclosing device, relatively movable contacts biased into engagement, electromagnetic means for sensing predetermined fault conditions of the controlled circuit and for initiating an opening operation of said device in response to such fault conditions, means responsive to operation of said electromagnetic means for separating said contacts, a rotatable member, a rack movable in response to operation of said electromagnetic means and in accordance with closing movements of said contacts, a timing mechanism operably connected with said rotatable member, an opening gear rotatable in response to an opening operation of said rack immediately following a prior operation thereof for rotating said member and for operating said timing mechanism to control the time required to open said contacts during preselected opening operations of said contacts, a closing gear rotatable in response to closing movement of said rack for rotating said member and for operating said timing mechanism to determine the time required automatically to reclose said contacts after an interrupting operation, means for limiting the rotation of said member to a predetermined amount to lock said closing gear against closing rotation thereby to hold said contacts in the open circuit position, and manually operable means for releasing said rack from said closing gear to cause said contacts to close due to the action of said means for closing said contacts.

CARL THUMIM.
